UNITED STATES PATENT OFFICE

JAMES BARON HARLEY, OF ENID, OKLAHOMA

LANTERN

Application filed May 3, 1929. Serial No. 360,165.

This invention is a signal lantern and has for its object the provision of a simple light and inexpensive lantern in which the light will be furnished by an electric current and will be visible from any point at which the lantern may be viewed. The invention provides a lantern which may be utilized as a spot light and also provides a lantern in which the light rays will be disseminated freely in all directions from the lantern. The invention is illustrated in the accompanying drawing and will be hereinafter fully set forth.

In the drawing:

Figure 1 is a sectional elevation of a lantern embodying the invention, and

Fig. 2 is a horizontal section on the line 2-2 of Fig. 1.

In carrying out the invention, there is provided a base 1 which is an opaque shell of metal tapering upwardly from its lower edge and having its lower edge entirely in one plane whereby it may rest upon a table or other support. At the top of the base 1, there is formed a chamber 2 by providing an annular rim coaxial with the base and having a horizontal partition 3 extending across the base at the top of the same, this partition also constituting the bottom of the chamber. At the center of the partition 3, there is formed a threaded socket 4 adapted to receive an electric lamp bulb 5, and to the under side of the partition is secured a parabolic reflector 6 concentric with said opening so that, when the lamp 5 is energized, the lantern may be utilized as a spot light, the base 1 serving to cut off the lateral rays from the lamp and the reflector directing the rays onto the spot which is to be illuminated. Upon the top edge of the bowl or chamber 2, there is hinged a metallic lid 7 which has its outer surface brightly polished so that it constitutes a parabolic reflector and at the center of this combined lid and reflector is a socket 8 adapted to receive an electric lamp bulb 9. Within the chamber 2 is a support 10 consisting of a block built up of layers of insulation, and through and upon this block are secured electric terminals 11 and 12 which are in the form of resilient fingers adapted to bear

against the central contact of the respective lamps, as shown clearly in Fig. 1. Fixed rigidly to the upstanding rim of the chamber 2 and extending upwardly therefrom are posts 13, at least one of which is hollow and serves as a conduit through which the wires 14 leading from the positive side of the battery are carried to be attached to the terminals 11 and 12, as will be understood. The battery is of the dry cell type and carried by a container 15 which is disposed between the upper ends of the posts 13 and is supported therefrom by braces 16, said braces being of metal and the container walls also of metal. Within the container is a wall or lining 17 of insulation which is spaced from the wall of the container and has its lower end also spaced from the bottom 18 of the container while on the under side of said bottom 18 is fixed a parabolic reflector 19. Carried by the bottom 18 of the container are negative contacts 20 which pass through the insulated bottom of the lining to make intimate contact with the negative side of the battery and at the center of the insulated lining is a contact 21 which bears directly against the positive electrode of the battery. An insulated wire 22 leads from the contact 21 under the bottom of the lining and then up through the space between the lining and the wall of the container to a pair of switches 23 and 24 which may be of any approved type. From the opposite ends of the switches, the wires 14 lead through the post 13 to the terminals 11 and 12, as has been stated. The posts 13 are reinforced at points intermediate their length or height by a reinforcing ring 25 and a similar ring 26 is preferably provided at the upper ends of the posts. Secured to the sides of the posts are arms 27 extending upwardly and fitted to a handle or bail 28 of wood or fiber or other insulating material whereby the lantern may be easily and comfortably carried and manipulated.

Within the chamber 2 are a plurality of spring clips 29 in which spare bulbs may be engaged and held so that should a bulb burn out a new bulb may be substituted therefor at once.

It is to be noted that the switches 23 and 24 are arranged upon the outside of the battery container and at such a point that they may be conveniently manipulated by the thumb of the user without releasing his hold upon the handle 28, and a cover 30 of any approved form may be provided over the container to prevent the battery cell from accidentally dropping therefrom. The braces 16 and the posts 13 constitute a metallic connection between the outer shell or wall of the battery container and the rim of the chamber 2 so that, when the cover 7 is closed, there will be a grounded return from the lamps 5 and 9 to the negative contacts 20 and through said contacts to the battery. The positive side of the battery is connected with the center contacts of the lamp through the wires and switches, as previously described, so that either lamp may be energized at will. The reflectors 7 and 19 are opposed to each other and the lamp 9 is disposed between them so that the light rays issuing from the lamp will be reflected in all directions laterally from the lantern and, consequently, the signals may be observed from any viewpoint. The posts and the reinforcing ring 25 form a very light skeleton frame for the lantern so that the obscuring of the light by parts of the frame is minimized and the disadvantage of the ordinary lanterns in this respect is overcome. When the spot light is to be used, the lamp 9 may be de-energized so that the only light issuing from the lantern will be that sent out by the lamp 5 and this light, of course, will be directed onto the spot which is to be examined. The positive conductors are very effectually housed by the wall of the battery container and the lining therefor and pass to the lamps through the hollow post 13 so that they are protected against accidental breakage and do not detract from the appearance of the device.

Having thus described the invention, I claim:

1. A lantern comprising a frame, a chamber carried by the frame, a reflector hinged to said chamber to constitute a lid therefor, a lamp mounted centrally upon said reflector, a second reflector carried by the frame in opposed spaced relation to the first reflector, the lamp being exposed between the two reflectors, and means for energizing the lamp.
2. A lantern comprising a base consisting of an imperforate upwardly tapered wall, a chamber carried by the top of said base, a reflector carried by the bottom of said chamber within the base, a lamp mounted at the center of the reflector, a cover for the chamber constituting a reflector, a lamp mounted externally of the chamber at the center of said cover, a frame including a hollow post fixed to and rising from said chamber, a battery carried by the frame, terminals within said

chamber engaging the respective lamps, and conductors leading from the battery through the hollow post to said terminals.

In testimony whereof I affix my signature.
JAMES BARON HARLEY. [L. S.]
